UNITED STATES PATENT OFFICE.

FREDERICK A. ANDERSON, OF WASHINGTON, DISTRICT OF COLUMBIA.

CURRENT-COLLECTOR FOR ELECTRIC RAILWAYS.

SPECIFICATION forming part of Letters Patent No. 593,154, dated November 2, 1897.

Application filed October 12, 1897. Serial No. 654,984. (No model.)

To all whom it may concern:

Be it known that I, FREDERICK A. ANDERSON, a citizen of the United States, residing at Washington, in the District of Columbia, have 5 invented certain new and useful Improvements in Current-Collectors for Electric Railways; and I do hereby declare the following to be a full, clear, and exact description of the invention, such as will enable others skilled 10 in the art to which it appertains to make and use the same.

This invention relates to current-collectors for electric railways.

The object is to provide a current-collector 15 in which all the exposed conducting parts shall be thoroughly insulated whereby to obviate danger of short-circuiting the current, as from accumulation of snow, slush, or ice on any projecting part; furthermore, to provide 20 a novel form of fuse connection the nature of which will be such as to permit of the ready replacing of a new fuse for one that is blown out without inconvenience to passengers of the car or danger to the workmen; 25 furthermore, to provide a shoe carried directly by the hanger or plow-standard, thereby to dispense with the employment of toggle-joints, pivoted links, and the like, such as are usually employed for this purpose, said shoe 30 being so mounted as to accommodate itself to any and all irregularities in the conducting-rail and also to occupy a position at all times in use normal to that of the said rail, irrespective of any inclination of the standard or 35 support; furthermore, to simplify the construction of the collector by reducing the number of its parts, thereby saving in material and minimizing the liability of derangement or injury in use, and, finally, to provide an 40 automatic lubricator to be used in connection with the standard-frame for oiling the same at its point of contact with the slot-rails.

In a current-collector characterized by my invention I provide an ordinary standard, 45 meaning thereby any suitable support comprising a plurality of frame-bars and copper conducting-bars insulated from the frame-bars by molded mica, slate, or porcelain, or any other suitable non-conducting substance, 50 the frame-bars being held assembled by means of two face-plates which are secured in place

by bolts passing through these plates and the frame-bars. The copper conducting-bars at the lower portion of the collector project through insulating-plates forming the exterior of the bottom portion of the plow, the plates being held in position upon the frame-bars by means of bolts suitably insulated therefrom, so that when the parts are assembled there can be no passage of current from 55 the conductor through this insulating-material. The shoes are each constructed of the usual contact-plate and insulating-block and are supported by means of brackets integral with or secured to the lower portion of the 60 collector, the brackets being provided with slots to permit of the shoes having the necessary range of lateral movement, and also to operate as stops, suitable bolts being provided for the purpose of holding the shoes in operative 65 position with relation to the brackets. To effect the proper contact between the shoes and the conducting-rails, springs are interposed between the insulating-blocks and the lower portion of the collector, the tension of 70 these springs being sufficient at all times to hold the shoes in contact with the said rails and to compensate for any irregularity in the same. By the arrangement described I dispense entirely with the employment of pivot- 75 ed hangers, toggle-joints, or other supports projecting outward from the collector and supported thereby, and also provide for the proper lateral and vertical oscillatory movement necessary to allow the shoe to accommodate 80 itself to any and all irregularities in the conducting-rail, and also to occupy a position at all times in use normal to that of the said rail, irrespective of any inclination of the standard or support. The shoes may be 85 electrically connected with the conducting-bars in any suitable manner, preferably, in this instance, by means of ordinary wires, the same being held at their ends by means of bolts, screws, or binding-nuts, carried, respectively, by the shoes and by the conducting-bars.

In order to support the lower ends of the conducting-bars and to afford efficient means for establishing electrical connection between 90 the shoes and the bars and also to remove strain from the screws holding the upper ends

the conducting-bars in position in the fuse blocks or boxes, I provide in this instance suitable supports, preferably of brass, which are secured to but insulated from the frame-bars, and are assembled with the copper conducting-bars by means of ordinary bolts passing through the two parts, the said bolts serving in this instance as a means for connecting the conductors from the shoes to the copper bars. The upper ends of the copper conducting-bars are housed in fuse blocks or boxes, thereby effectually insulating this portion of the conducting-bars from the frame-bars, and housed within another portion of each of these fuse-blocks is one of the terminals, the terminal and conducting-bar being connected by an ordinary fuse. As before stated, it is desirable that the fuses should be arranged in such position upon the collector as to be readily accessible for the purpose of repair in case they should blow out, and to this end they are located quite close to the top of the collector, and in order to obviate the danger of a shock to a person in repairing a break there are insulating sheets or blocks covering the fuse blocks or boxes, and against the outer faces of these insulating-sheets the two ends of each of the fuses are secured by means of ordinary binding or thumb-nuts having, preferably, insulated bases. Thus to replace a fuse for one that is blown out it will only be necessary to lift the ordinary trap-door provided in the floor of the car, loosen two thumb-nuts, replace a new fuse for one that is destroyed, and again tighten the thumb-nuts. By this arrangement in case a fuse blows out the outer insulating-body covering the fuse block or box will receive the shock, and, if destroyed, may be replaced at but a small cost. It is to be understood that the arrangement of the shoes, conducting-bars, and fuses is the same on both sides of the collector, and for this reason a description of one will serve for both.

Arranged upon each side of the collector at the point where it works between the slot-rails I provide a wear-plate, preferably of case-hardened steel, and arranged also upon each side of the collector is a lubricating device which will supply oil to the said plates at the point of wear. By this arrangement the life of the wear-plates may be extended indefinitely, and rusting, as from moisture, will also be avoided.

Further and more specific details of construction will be hereinafter more fully described and claimed.

In the accompanying drawings, forming a part of this specification and in which like letters of reference indicate corresponding parts, I have illustrated a form of embodiment of my invention, although it is to be understood that other forms of embodiment thereof may be employed without departing from the spirit of the same, and in these drawings—

Figure 1 is a view in elevation, partly in section, showing the collector in position between two slot-rails, with the shoes in engagement with the conducting-rails. Fig. 2 is a view in side elevation, partly in section, showing the relative arrangement of the parts constituting the collector. Fig. 3 is an edge view showing in detail certain parts omitted in Fig. 1. Fig. 4 is a longitudinal sectional view taken on the line 4 4, Fig. 2. Fig. 5 is a similar view taken on the line 5 5, Fig. 2. Fig. 6 is a similar view taken on the line 6 6, Fig. 2. Fig. 7 is a similar view taken on the line 7 7, Fig. 2. Fig. 8 is an enlarged detail view in section showing more particularly one manner of mounting the shoe upon the collector to allow the shoe to have the necessary lateral and oscillatory movements to accommodate itself to any irregularity in the conducting-rails and the manner of supporting the lower end of the copper conducting-bar. Fig. 9 is a detached detail view showing the knife-edge switch at the top of the standard.

In explaining this invention but one-half of the collector will be described, as it will be understood that both sides are exactly the same.

Referring to the drawings, A and A² designate two frame-bars, which, for the purpose of providing sufficient rigidity and strength to the collector, are constructed of iron or tool-steel, and A³ the copper conductors for conveying the current from the shoe to one terminal and from the latter through the car back to the other terminal, and so on to the other shoe.

The collector herein shown consists of four frame-bars and two copper conducting-bars. These bars are held assembled at the top of the collector by means of face-plates A⁴, which may be of any suitable material, such as iron or steel, and at the bottom portion of the collector by means of metallic cross or connecting plates A⁵, also of iron or steel, suitable bolts being passed through the plates and the frame-bars only for holding the parts assembled. By the arrangement described there is a considerable space left between the respective frame-bars, which arrangement lightens the plow or collector.

At a point intermediate of the two ends of the collector and on each side thereof there is secured a wear-plate A⁶, which is arranged at that point of the plow which will contact with the slot-rails, the said plates being held in place by means of bolts passing through the same and through the frame-bars. These plates A⁶ subserve a double function, the first of which, as their name indicates, being to prevent wear to the standard. The second and probably most important function is that of preventing any short-circuiting between the conducting-bars and the slot-rails. As here shown, the wear-plates extend from a point near the bottom to a point somewhat

above the middle of the plow; but it is to be understood that I do not limit myself to this exact arrangement, as the plates may be made longer and wider if preferred or if found convenient or necessary.

The lower portions of the frame-bars are covered or incased by two sheets of insulating material A⁷, which may be of any desired substance suitable for the purpose and are secured to the frame-bars by means of bolts A⁸, insulated by collars from the frame-bars, as clearly shown by reference to Fig. 2. Supported on each side of the lower portion of the collector and secured to these insulating plates are two brackets A⁹ and A¹⁰, respectively, the same being provided with flanges through which bolts A¹¹ are passed for securing the brackets in position, these bolts being also insulated in the manner described. These brackets are each provided with a slotted boss or extension A¹², which is best shown in Fig. 8, and between these extensions are mounted insulating-blocks A¹³, provided with the usual conducting-shoes A¹⁴, the blocks being held in place by means of bolts A¹⁵, mounted in the slots of the brackets. These slots are of such length as to permit of the shoes having the requisite lateral and vertical oscillatory movement to compensate for any inequality in the conducting-rails and also permits of the shoes having movement about shifting axes lying in planes at right angles to each other, so that the contact-face of a shoe will always occupy a position normal to that of the conducting-rail, irrespective of any inclination assumed by the standard or support, as in rounding curves, the outer ends of the slots serving effectually as stops to limit the lateral movement of the shoes. In order to keep the shoes in operative contact with the conducting-rails, springs A¹⁶ are provided, the base or body portions of which are bolted against the insulation at the base of the collector, and their free ends are bowed or bent, so as to bear against the insulating-blocks. The insulating-blocks and shoes are held assembled by means of bolts A¹⁷. The shoe is provided on one side with a boss A¹⁸, to which is connected one end of a conducting-wire A¹⁹, the other end of which is connected with a bolt A²⁰, passing through a metallic block A²¹ and through a toe A²², formed by turning outward the lower end of the conducting-bar A³, an opening being provided in the insulating-plate A⁷ for this purpose, as will be clearly seen by reference to Fig. 8. The purpose of this block A²¹ is to support the lower end of the conducting-bar and also to remove strain from the bolt or screw at the upper end, to which the fuse is connected, this bar A³ being completely insulated from the frame-bars by any suitable insulating material, as will be seen by reference to Fig. 8.

The frame-bars A² do not extend to the top of the collector, but terminate some distance below the same in order to form space in

which to fit a fuse block or box A²³, the same being held in position by means of bolts or screws passing through ears A²⁴, provided for the purpose. This fuse block or box is provided with two openings, in one of which is housed the upper end of the conducting-bar A³ and in the other the lower end of a terminal, and over the terminal and the end of the copper conducting-bar is placed a plate of insulating material A²⁵, as clearly shown in Figs. 1 and 3, thus completely shielding these parts from exposure and danger of contact. Arranged exteriorly of the plate A²⁶ is the fuse A²⁷, which may be of any preferred type and is operatively connected with the conducting-bar and the terminal by means of screws or bolts carrying thumb-nuts A²⁸, which when seated serve to bind the fuse against the insulating-plate A²⁶. It will be seen that when the fuse is secured in place it will occupy a position exterior of the collector, so as to be readily accessible for the purpose of repair, to accomplish which it will only be necessary to remove the two thumb-nuts, replace a new fuse, and seat the thumb-nuts in place, as already described.

To prevent undue wear of the plates A⁶ and also to guard against rust, I provide on each side of the plow a lubricator A²⁹, provided with an extension or tube A³⁰, terminating at a point near where the wear-plates contact with the slot-rails. This lubricator may be of the sight-feed style, so as to prevent undue waste of the lubricant.

In order further to guard against any possibility of an operator receiving a shock while replacing a blown-out fuse, I may interpose between the fuse-block and the shoe at any convenient point an ordinary switch, as a knife-switch A³¹, as shown in Fig. 9, which, by being thrown back, will cut off the current to the fuse and thereby render the binding-posts of the same dead.

To prevent an accumulation of ice, snow, or slush from short-circuiting the current between the toes A²² of the conducting-bars and any part of the plow-standard, I provide insulating extensions or ledges A³¹ immediately over these toes, as will be clearly seen by reference particularly to Figs. 1, 3, and 8, thereby effectually obviating any danger of establishing a short circuit at these points.

It is to be understood that I do not limit myself to the exact manner of connection between the shoe and the conducting-bar—that is to say, the precise arrangement herein shown—as it will be obvious that other forms of connection may be employed without departing from the spirit of my invention; also, that I do not limit myself to the exact manner of mounting or supporting the shoe, the point of the invention in this respect being to mount the shoe in any suitable manner (one manner for the purpose being that shown) by which it will have vertical and longitudinal oscillatory and lateral movement.

Having thus fully described my invention, what I claim as new, and desire to secure by Letters Patent of the United States, is—

1. In a current-collector, a standard comprising a plurality of frame-bars, conducting-bars arranged between the frame-bars and insulated therefrom, terminals arranged at the top of the standard, fuse-blocks arranged in the upper portion of the standard and having recesses in which the upper ends of the conducting-bars and the lower ends of the terminals are housed, whereby to insulate these parts from each other, fuses arranged exteriorly of the sides of the fuse-blocks and on opposite sides of the standard, and means to permit the ready removal and replacement of the fuses, substantially as described.
2. In a current-collector, a standard comprising a plurality of frame-bars, conducting-bars arranged between the frame-bars and insulated therefrom, terminals arranged at the top of the standard, fuse-blocks arranged in the upper portion of the standard and having recesses in which the upper ends of the conducting-bars and the lower ends of the terminals are housed, whereby to insulate these parts from each other, fuses arranged exteriorly of the fuse-blocks and on diagonally opposite sides of the standard, and means to permit the ready removal and replacement of the fuses, substantially as described.
3. In a current-collector, a standard comprising a plurality of frame-bars, conducting-bars arranged between the frame-bars and insulated therefrom, wear-plates secured intermediate of the ends of the frame-bars and insulated therefrom, and operating to protect the frame-bars, and, also, to prevent short-circuiting between the conducting-bars and the slot-rails, insulating-plates secured below the wear-plates, brackets rigidly secured against the insulating-plates, contact-shoes supported from the brackets, and electrical connections between the shoes and the conducting-bars, substantially as described.
4. In a current-collector, a standard comprising a plurality of frame-bars, conducting-bars arranged between and insulated from the frame-bars, fuse-blocks in which one end of the terminals and the conducting-bars are housed, and a switch on each of the fuse-blocks between the terminal and the conducting-bar, substantially as described.
5. In a current-collector, a standard comprising a plurality of frame-bars, conducting-bars arranged between and insulated from the frame-bars, fuse-blocks in which one end of the terminals and the conducting-bars are housed, and a knife-edge switch on each of the fuse-blocks between the terminal and the conducting-bar, substantially as described.
6. In a current-collector, a standard comprising a plurality of frame-bars, conducting-bars arranged between and insulated from the frame-bars, fuse-blocks in which one end

of the terminals and the conducting-bars are housed, a surface of insulating material on each fuse-block, a fuse held in place against each surface of insulating material, and a switch on each fuse-block between the terminals and the conducting-bar, substantially as described.

7. A current-collector having a knife-edge switch between each terminal and its corresponding shoe, the handle of the switch being disposed downward, substantially as described.

8. A current-collector having wear-plates, and lubricating devices for supplying a lubricant to the plates at the points where they contact with the slot-rails, substantially as described.

9. A current-collector comprising a standard and a shoe carried thereby, the shoe being mounted for movement about shifting axes lying in planes at right angles to each other, whereby the contact-face of the shoe will always occupy a position normal to that of the conductor, irrespective of any inclination of the shoe-standard, substantially as described.

10. A current-collector comprising a standard and a spring-pressed shoe carried thereby, the shoe being mounted for movement about shifting axes lying in planes at right angles to each other, whereby the contact-face of the shoe will always occupy a position normal to that of the conductor, irrespective of any inclination of the shoe-standard, substantially as described.

11. In an electric railway employing a flat conductor, a shoe mounted for movement about shifting axes lying in planes at right angles to each other, whereby the contact-face of the shoe will always occupy a position normal to that of the conductor, irrespective of any inclination of the shoe-standard, substantially as described.

12. In an electric railway employing a flat conductor, a spring-pressed shoe mounted for movement about shifting axes lying in planes at right angles to each other, whereby the contact-face of the shoe will always occupy a position normal to that of the conductor, irrespective of any inclination of the shoe-standard, substantially as described.

13. In a current-collector, a standard comprising a plurality of frame-bars, conducting-bars arranged between and insulated from the frame-bars, insulating material covering both sides of the lower portion of the standard, brackets rigidly secured against the insulating material, shoes supported from the brackets, and connections between the shoes and the conducting-bars, substantially as described.

14. A current-collector comprising a standard carrying two sets of brackets provided with slots, bolts passing through the slots and through insulating-blocks mounted between the brackets, shoes carried by the blocks, and springs interposed between the standard and

the insulating-blocks, substantially as described.

15. In a current-collector, a standard having pairs of brackets secured on each side of its lower portion, each pair being provided with slots disposed in vertical alinement, insulating-blocks working between the brackets, bolts passing through the slots and through the insulating-blocks, shoes carried by the blocks, and springs interposed between the blocks and the standard, substantially as described.

16. A current-collector having the lower portion of its sides covered by sheets of insulating material, brackets secured against this insulating material, said brackets being provided with slots disposed in vertical alinement, insulating-blocks working between the brackets, bolts passing through the slots and through the insulating-blocks, and shoes carried by the blocks, substantially as described.

17. In a current-collector, a standard comprising a plurality of frame-bars, conducting-bars arranged between the frame-bars and insulated therefrom, each conducting-bar having its lower portion provided with an outturned toe, face-plates secured on each side of the standard, and holding the frame-bars and conducting-bars assembled, wear-30 plates secured to the said bars, an insulating-plate secured on each side of the lower portion of the standard, and provided, each, with an opening, through which extends the toe of a conducting-bar, conducting-blocks secured to the plow below these toes, insulating material arranged above the toes, whereby to prevent short-circuiting between the toes and the standard, transversely-slotted brackets secured on each side of the 35 lower portion of the plow against the insulating-plates, blocks mounted between the brackets and held in place by bolts passing through the slots in the brackets, shoes carried by the blocks, and electrical connections 40 between the shoes and the conducting-bars, substantially as described.

45. A current-collector comprising a stand-

ard composed of a plurality of frame-bars, conducting-bars arranged between the frame-bars and insulated therefrom, each conducting-bar having its lower portion provided with an outturned toe, face-plates secured on each side of the standard and holding the frame-bars and conducting-bars assembled, wear-50 plates secured to the said bars, an insulating-plate secured on each side of the lower portion of the standard and provided, each, with an opening through which extends the toe of a conducting-bar, conducting-blocks secured to the standard below these 55 toes, insulating material arranged above the toes, whereby to prevent short-circuiting between the toes and the plow, transversely-slotted brackets secured on each side of the lower portion of the standard against the 60 insulating-plates, blocks mounted between the brackets and held in place by bolts passing through the slots in the brackets, shoes carried by the blocks, electrical connections between the shoes and the conducting-bars, 65 fuse-blocks carried by the upper portion of the standard, fuses held in place against the blocks and connecting the terminals and the conducting-bars electrically, and a switch between each terminal and its corresponding 70 shoe, substantially as described.

19. In a current-collector, a standard carrying shoes, fuse-blocks arranged in the upper portion of the standard and provided with recesses, terminals having their lower 75 ends housed in the fuse-blocks, conducting-bars having their upper ends housed in the fuse-blocks and their lower ends in electrical connection with the shoes and a switch on each of the fuse-blocks between the terminal 80 and the conducting-bar, substantially as described.

In testimony whereof I affix my signature in presence of two witnesses.

FREDERICK A. ANDERSON.
